CRUSHER

David Cole, El Paso, Tex.

Application July 1, 1932, Serial No. 620,517

16 Claims. (Cl. 83—10)

This invention relates to crushers and particularly to gyratory crushers intended for use in fine crushing, of which the shorthead Symons cone crusher is typical.

5 In developing a cone crusher for fine crushing work, according to the well known Symons principles, it was found expedient to lessen the height of the head by elimination of the upper portion, and to devote a large proportion of its 10 effective crushing area to the production of fines. The effect of this was to reduce greatly the maximum size stone that the crusher will take and to reduce the entrance flare between the head and bowl so that the range of sizes in the feed must 15 be much more closely controlled than in the prior types of Symons crusher. This limitation impairs the availability of the shorthead crusher and of any similarly designed fine crushing gyratory crusher for use in further crushing 20 product from existing and less highly developed preparatory crushing equipment.

The material which is to be fed to shorthead and like crushers, must be prepared in a coarse crusher. This may or may not be of the gyratory 25 type. Regardless of type, existing machines may be expected to deliver a small percentage of so-called oversize in the product. Thus, if the "set" is 2", the product will have from 3% to 10% of pieces which will exceed 2", i. e., irregular shaped 30 pieces which will not enter a 2" gap at the entrance of shorthead cone crushers. In practice these oversize pieces accumulate on the feed table in the hopper from which the shorthead crusher is fed, and eventually occupy this hopper to the 35 exclusion of other feed. The effect is to put the shorthead crusher out of action.

To "set" the preceding coarse crusher so close as to ensure that its entire output would enter the 2" gap at the entrance of the shorthead crusher, 40 would be to reduce greatly the capacity of the coarse crusher, overstrain it, and add very materially to the cost of the preparatory crushing work.

The present invention overcomes the difficulty 45 by modifying the shorthead or fine crushing crusher in such a way as to impart to it a capacity to accept at least a limited amount of oversize feed without materially reducing its capacity and without impairing its effectiveness. The invention 50 involves the discovery that even the limited flare zone of the present shorthead crushers is more than ample to provide feed to the fine crushing and sizing zone so that it is possible 55 to sacrifice a small percentage of the crushing area in the entrance flare zone and apply this area to the crushing of oversize. In this way the burden of taking care of the oversize is placed on the fine crusher. The effect is to increase the 60 availability of the fine crusher with respect to the

acceptance of feed of varying sizes without impairment of its crushing functions.

The preferred arrangement is to provide one or more pockets at the entrance periphery of the bowl liner, the pockets being arranged to catch and crush the stray oversize pieces as they arrive with the feed. Such pocket or pockets may, however, be formed in the head mantle instead of being formed in the bowl liner, or they may be formed both in the head mantle and in the 10 bowl liner. In the latter case, if the numbers of pockets in the head mantle and in the bowl liner are incommensurate, a hunting effect can be secured with desirable results.

15 The possibility of forming pockets of the substantial dimensions necessary to receive oversize pieces, without materially reducing the effective crushing area of the flaring entrance zone, arises from the fact that in "shorthead" and similar crushers the entrance interval between the head 20 and bowl is small as compared to the diameter of the head at the entrance. Thus a pocket large enough to receive a piece whose diameter is say 1.5 the normal size will occupy only a small fraction 25 of the entrance periphery of the head or bowl as the case may be.

I prefer a form of pocket which increases in depth and in width toward the entrance to the flaring entrance zone, and thus provides a limited 30 area in which the entrance flare is increased, but the invention is not limited in this respect.

Several embodiments of the invention are illustrated in the accompanying drawings, in which,—

Fig. 1 is a vertical axial section of a Symons 35 type of crusher with the invention applied in its preferred form.

Fig. 2 is a view showing the form of the crushing surfaces, i. e., the head mantle and the bowl liner in their proper relation to each other, as heretofore used in shorthead cone crushers.

40 Fig. 3 is a similar view showing a modification of the invention in which the pockets are formed at the entrance periphery of the head mantle.

Fig. 4 is a similar view showing a modification 45 of the invention in which the pockets are formed at the entrance periphery of both the head mantle and the bowl liner.

Fig. 5 is a section on the line 5—5 showing incommensurate spacings of the pockets in the head mantle and bowl liner serving to cause the pockets 50 to "hunt".

In the drawings, 11 represents a portion of the base frame in which turns the sleeve 12. The gyrating crushing head 13 is carried on a tapered spindle 14 which is journaled in the sleeve 12 on an inclined, eccentric axis, as usual. The usual dust excluding members are shown at 15, and the bevel drive gears for the sleeve 12 appear at 16 and 17.

The head 13 carries the usual cone or mantle 60

18 which forms the working surface of the head and is retained on the head 13 by a disk 19 held by screws 21. The disk 19 serves as a feed table. Overhanging the cone 18 is a bowl which in practice takes the form of a removable liner 22 supported in any suitable manner by the head ring 23. The head ring 23 supports a feed hopper 24 within which the feed controlling sleeve or ring 25 is mounted. The ring 25 is vertically adjustable by means of the rack 26 and adjusting wheel 27.

15 The parts above described conform to standard construction, with the exception of the working surfaces of the head and bowl. The head or the bowl is, or both are, modified by adding pockets at the entrance periphery.

20 Referring to Fig. 2, which shows the standard Symons cone and bowl, it will be observed that the cone 18a has an entrance cone portion 31a and a fine crushing and sizing cone portion 32a, while the bowl 22a has an entrance cone portion 33a and a fine crushing and sizing cone portion 34a.

25 As will be apparent to those familiar with Symons crushers, the opposed conical portions 31a and 33a provide the entrance flare, which in shorthead crushers is short and not very flaring as compared to the coarse crushers. The opposed conical portions 32a and 34a provide the well known "zone of parallelism" which in the case of the shorthead crushers is long, and for fine crushing, very narrow.

30 In Fig. 1, cone 18 is identical with cone 18a, having portions 31 and 32 corresponding to 31a and 32a. The bowl 22 differs from 22a for while it has an area 34 similar to 34a, the area 33 is interrupted by tapered or triangular pockets 35 widest at the entrance periphery and tapering to disappearance slightly below the line of junction 40 of the conical surfaces 33 and 34.

35 In Fig. 3 bowl 22b is essentially identical with standard bowl 22a but the cone 18b has pockets 36 similar in form and location to the pockets 35.

40 In Fig. 4 is shown bowl 22c having pockets 37 similar to pockets 35 and a cone 18c having pockets 38 similar to the pockets 36. These may be variously spaced, but Fig. 5 shows four pockets 37 in the bowl and three pockets 38 in the cone. This disparity of interval ensures that only one 45 pair of pockets 37, 38, can oppose each other at a time, the numbers being incommensurate or prime to one another. Opposed pockets will take the extremely large oversize which is rare. Individual pockets will take smaller oversize.

50 It is preferred to locate the pockets in the bowl as shown in Fig. 1. If the bowl should split through a pocket the bowl would still be sustained because it cannot expand; but if a cone should split it is likely to wreck the machine. Hence it is preferred to form no recesses in the cone. Their presence in the bowl involves no risk.

55 The number of pockets is a matter of design. Two of them are ordinarily sufficient and occupy less than 5% of the crushing area. Four pockets 60 occupying about 1/2 of the entrance, and reducing the crushing area by less than 10% would enable a crusher intended for 2" feed to take as much as 20% of the feed up to 3 1/2". The modified crusher will crush as fast and nearly if not quite as fine as the original shorthead crusher, and such modification greatly relaxes the requirements imposed on the coarse or feeding crusher. This is 65 peculiarly important when old crushing equipment is to be used to prepare the feed for the fine crusher.

10 It is the relatively large entrance diameter as compared to the small entrance interval between head and bowl, that permits the use of one or more pockets of substantial size without reducing unduly the normal crushing surface of the flaring entrance zone. An important aspect of the invention is that the pockets occupy only a small fraction (of the order of 5% to 10%) of the flaring zone, so that the effectiveness of the crusher is not materially affected.

15 While I prefer triangular pockets, as shown, i. e., pockets which become narrower and shallower at the same time, modifications of form are possible and will readily suggest themselves.

20 It is preferred to operate the crusher with controlled feed and at the rates characteristic of the Symons crushing process (see Patent No. 1,537,565, May 12, 1925) so that the particles are crushed between the cone and mantle and move freely between crushing impacts, but this is not necessary in all cases. The invention is broadly applicable and not limited to use with the Symons apparatus or process.

25 What is claimed is,—

1. The combination of a crushing head; an encircling bowl; and means for imparting relative gyratory motion thereto, said head and bowl co-operating to form a flaring entrance zone narrow relatively to the diameter of the head at the entrance, and a fine crushing zone, at least one of said head and bowl members having a pocket in the flaring entrance zone to receive and crush oversized feed, the width of said pocket exceeding the maximum separation between said head and bowl members at the entrance to said flaring zone.

2. The combination of a crushing head; an encircling bowl; and means for imparting relative gyratory motion thereto, said head and bowl co-operating to form a flaring entrance zone narrow relatively to the diameter of the head at the entrance, and a fine crushing zone, said head and bowl each having a pocket in the flaring entrance zone to receive and crush oversized feed, the widths of said pockets each exceeding the maximum separation between said head and bowl at the entrance to said flaring zone.

3. The combination of a crushing head; an encircling bowl; and means for imparting relative gyratory motion thereto, said head and bowl co-operating to form a flaring entrance zone narrow relatively to the diameter of the head at the entrance, and a fine crushing zone, said head and bowl respectively having unequal numbers of pockets in the flaring entrance zone to receive and crush oversized feed, the widths of said pockets each exceeding the maximum separation between said head and bowl at the entrance to said flaring zone.

4. The combination of a crushing head; an encircling bowl; and means for imparting relative gyratory motion thereto, said head and bowl co-operating to form a flaring entrance zone narrow relatively to the diameter of the head at the entrance, and a fine crushing zone, said bowl having a pocket in the flaring entrance zone to receive and crush oversized feed, the width of said pocket exceeding the maximum separation between said head and bowl at the entrance to said flaring zone.

5. The combination of a crushing head; an encircling bowl; and means for imparting relative gyratory motion thereto, said head and bowl co-operating to form a flaring entrance zone narrow relatively to the diameter of the head at the en-

- trance, and a fine crushing zone, at least one of said head and bowl members having a pocket formed in the entrance zone, said pocket flaring in width and depth from near the junction of the 5 two zones to the entrance to the flaring zone, the width of said pocket at the entrance to the flaring zone exceeding the maximum separation between said head and bowl members at the entrance to said flaring zone.
- 10 6. The combination of a crushing head; an encircling bowl; and means for imparting relative gyratory motion thereto, said head and bowl cooperating to form a flaring entrance zone narrow relatively to the diameter of the head at the entrance, and a fine crushing zone, said head and bowl each having a pocket formed in the entrance zone, said pocket flaring in width and depth from near the junction of the two zones to the entrance to the flaring zone, the widths of said pockets at such entrance each exceeding the maximum separation of the head and bowl at such entrance.
- 15 7. The combination of a crushing head; an encircling bowl; and means for imparting relative gyratory motion thereto, said head and bowl cooperating to form a flaring entrance zone narrow relatively to the diameter of the head at the entrance, and a fine crushing zone, said bowl having a pocket formed in the entrance zone, said pocket flaring in width and depth from near the junction of the two zones to the entrance to the flaring zone, the width of said pocket at such entrance exceeding the maximum separation of the head and bowl at such entrance.
- 20 8. The combination of a crushing head; an encircling bowl; and means for imparting relative gyratory motion thereto, said head and bowl cooperating to define a flaring entrance zone and a fine crushing zone, at least one of said head and bowl members having a pocket dimensioned to permit entrance between the head and bowl of a piece of the order of 50% oversize, said pocket occupying 5% or less of the total crushing area.
- 25 9. The combination of a crushing head; an encircling bowl, said head and bowl having each two conical portions which coact to form a flaring entrance zone narrow relatively to the diameter of the head at the entrance, and a zone of parallelism; and means for imparting relative gyratory motion to the head and bowl, there being in the entrance zone in one of said head and bowl members at least one tapered pocket having a greater entrance flare than the entrance zone, the width of said pocket at its entrance exceeding the maximum separation between the conical surfaces of the head and bowl at such entrance.
- 30 10. The combination of a crushing head; an encircling bowl, said head and bowl having each two conical portions which coact to form a flaring entrance zone narrow relatively to the diameter of the head at the entrance, and a zone of parallelism; and means for imparting relative gyratory motion to the head and bowl, there being in the entrance zone in the head at least one tapered pocket having a greater entrance flare than the entrance zone, the width of said pocket at its entrance exceeding the maximum separation between the conical surfaces of the head and bowl at such entrance.
- 35 11. The combination of a crushing head; an encircling bowl, said head and bowl having each two conical portions which coact to form a flaring entrance zone narrow relatively to the diameter of the head at the entrance, and a zone of parallelism; and means for imparting relative gyratory motion to the head and bowl, there being in the entrance zone in the bowl at least one tapered pocket having a greater entrance flare than the entrance zone, the width of said pocket at its entrance exceeding the maximum separation between the conical surfaces of the head and bowl at such entrance.
- 40 12. The combination of a crushing head; an encircling bowl, said head and bowl having each two conical portions which coact to form a flaring entrance zone narrow relatively to the diameter of the head at the entrance, and a zone of parallelism; and means for imparting relative gyratory motion to the head and bowl, there being in the entrance zone in the head and in the bowl at least one tapered pocket having a greater entrance flare than the entrance zone, the entrance widths of said pockets each exceeding the maximum separation between the conical portions of said head and bowl.
- 45 13. The combination of a crushing head; an encircling bowl; and means for imparting relative gyratory motion thereto, said head and bowl cooperating to define a flaring entrance zone and a fine crushing zone, at least one of said head and bowl members having a pocket dimensioned to permit entrance between the head and bowl of a piece of the order of 50% oversize, said pocket occupying 5% or less of the total crushing area.
- 50 14. The combination of a crushing head; an encircling bowl; and means for imparting relative gyratory motion thereto, said head and bowl cooperating to define a flaring entrance zone and a fine crushing zone, the bowl member having a pocket dimensioned to permit the entrance between the head and bowl of a piece of the order of 50% oversize, said pocket occupying 5% or less of the crushing area.
- 55 15. The combination of a crushing head; an encircling bowl; and means for imparting relative gyratory motion thereto, said head and bowl cooperating to form a narrow flaring entrance zone and a fine crushing zone to which the flaring entrance zone delivers partially crushed material, said bowl having a pocket at the entrance to the flaring zone, said pocket being of a width such as not to be bridged by such oversize piece, and the total pocket area being not to exceed 10% of the total crushing area.
- 60 16. The combination of a crushing head; an encircling bowl, said head and bowl having each two conical portions which coact to form a flaring entrance zone narrow relatively to the diameter of the head at the entrance, and a zone of parallelism; and means for imparting relative gyratory motion to the head and bowl, there being in the entrance zone in the head and in the bowl pockets having a greater entrance flare than the entrance zone, the numbers of pockets in the head and bowl being prime to one another and the entrance widths of such pockets each exceeding the maximum separation between the conical portions of said head and bowl.
